CARGO TESTER WHICH SIMULATES SHIP'S MOTION

Filed July 1, 1947

UNITED STATES PATENT OFFICE

2,614,413

CARGO TESTER WHICH SIMULATES
SHIP'S MOTION

Henry G. Alley, Jr., Colonial Heights, Va.

Application July 1, 1947, Serial No. 758,459

5 Claims. (Cl. 73—12)

(Granted under the act of March 3, 1883, as
amended April 30, 1928; 370 O. G. 757)

1

The invention described herein, if patented may be manufactured and used by or for the Government for governmental purposes, without the payment to me of any royalty thereon.

This invention relates to testing apparatus and has for its primary object to provide a device which will simulate the movements of a ship and which is capable of receiving a load of cargo stacked in substantially the same manner that it would be stacked in the hold of a ship, so as to transmit to the cargo the stresses and strains it would receive if in transit, to thereby determine whether or not the packaging is sufficiently strong and durable, or whether or not the packaging might be reduced as to strength or quality with a consequent saving in packaging costs.

Another object of the invention resides in the provision of such a device which may be easily installed and operated and which is sufficiently strong to permit repeated testing operations over a long period of time under heavy loads without appreciable deterioration.

Other objects and advantages of the invention will be apparent from the following description when taken in connection with the accompanying drawings, in which,

Figure 1 is a vertical sectional view through the base of the testing device with a load of cargo mounted thereon, the superstructure being shown in elevation.

Figure 2 is an elevational view of the apparatus taken at an angle of 90° from the showing of Figure 1.

Figure 3 is a horizontal sectional view, partly broken away, taken on the line 3—3 of Figure 1.

Figure 4 is a plan view of the apparatus with the cargo omitted; and

Figure 5 is a perspective view of the testing device loaded and ready for oscillation or rotation.

In the present embodiment of the invention, the base member includes a block of concrete 1 molded in a cavity in the ground and substantially flush with the latter, and an annular series of wedges 2 which have upper surfaces of arcuate form so as to provide a dished formation.

The inner ends of the wedges 2 terminate short of the center of the circle of which they form a part and provide for the installation of a ball and socket joint to be associated with the rockable member which supports the goods to be tested. The socket 3 of the ball and socket member is anchored in the body of the concrete base 1 by means of a plurality of extensions 4 which

2

radiate from the base of the socket member. The ball of the ball and socket joint is indicated by the numeral 5 and is provided with a pin 6 which is slidably received in the central groove or slot 7 of the rockable member.

The rockable and oscillatable part of the testing apparatus may take various forms but in the present illustration is shown as a substantially hollow semi-circular body formed of metal and indicated by the numeral 8. Welded to the inner portion of the member 8 and centrally thereof is a sleeve 9 in which the slot 7 is formed and the interior of member 8 is shown as filled with concrete or the like 10 which serves as a foundation for supporting the goods to be tested.

In the present instance the articles being tested are shipping crates or boxes for burial caskets and these articles are referred to by numeral 11. For the purpose of supporting a stack of these crates or other proposed cargo a plurality of crossbeams 12 and 13 are fixed to the upper surface of the rockable member 8 and are provided at their ends with apertures for receiving clamping bolts 14. A framework comprising crossbars 15 and 16 is provided for placement upon the stack of articles being tested and these crossbars are also provided with apertures at their ends for reception of the free ends of the retaining or clamping bars 14 so that the stack of articles may be loosely or tightly secured to the rockable member 8 as desired. Moreover, these clamping bars or rods serve as guard members to prevent the accidental displacement of any of the articles in the stack being tested.

As a safety feature for preventing the secured load and rockable member 8 from possibly becoming overbalanced and tilting beyond the design safety angle, it is desirable to provide four poles 17 spaced a slight distance away from the apparatus and 90° apart. Cables with the desired amount of slack are secured to these poles adjacent to the tops thereof and the opposite ends of the cables may be suitably secured to a ring 18 on the upper framework 15—16, as clearly indicated. Also, fixed to the upper framework 15—16 are a plurality of ropes 19 for imparting the desired movements to the testing apparatus.

As will be apparent by an inspection of Figures 1 and 2 of the drawings, the rockable member 8 together with the load clamped thereon may be rocked or rolled on the dish-shaped element formed by the annular series of the concaved wedges, but it may also be rocked back and forth in a single plane. If the apparatus is to be rocked back and forth in a single plane in simulation of

the rolling or pitching action of a ship, it will be understood that two diametrically opposed ropes 19 will first be secured to the two poles 17 adjacent the bottoms thereof in the same plane and the rockable member will be oscillated back and forth in the plane of the other two diametrically opposed ropes 19 which are free. Should it be desired to rock the testing device in a plane at right angles to the plane just mentioned, it will of course be necessary to secure the two free ropes 19 just mentioned and release the other ropes 19 so that the testing apparatus may be oscillated in this second plane. Moreover, when it is desired to rotate or roll the member 8 all of the ropes 19 will be released or at least provided with sufficient slack so that by proper manipulation of these ropes 19 the member 8 may be rolled about the dished member formed by the wedges 2. In this movement, as well as in the oscillation of the member 8, the pin and slot connection provides the necessary freedom of action of the rockable member 8. These various movements of the member 8 impart to the load of articles clamped thereto the various stresses and strains in much the same manner as they would be received when stacked in a ship and consequently it is possible not only to determine in advance of shipment whether or not the packaging is adequate but also to determine to some extent whether or not the packaging might be reduced in strength or quality and a consequent saving in packaging expense.

While the apparatus has been described in considerable detail it will be readily understood that many of the details may be altered or entirely omitted without departing from the spirit of the invention and it is therefore intended that the present disclosure be considered as illustrative of the invention rather than in a limiting sense.

I claim:

1. A testing device for cargo adapted to simulate the movements of a ship, comprising a dished base member, a rockable member having a rounded bottom mounted in the base member, means for securing cargo on the rockable member, and means for rocking the rockable member.

5 2. A testing device for cargo adapted to simulate the movements of a ship, comprising a dished base member and a cargo-supporting member mounted in the base member and provided with a rounded bottom having a radius of curvature smaller than the radius of curvature of the base member.

10 3. A testing device for cargo adapted to simulate the movements of a ship, comprising a dished base member, a cargo-supporting member mounted in the base member and provided with a rounded bottom having a radius of curvature smaller than the radius of curvature of the base member, and a slidable connection between the base member and cargo-supporting member.

15 4. A testing device for cargo adapted to simulate the movements of a ship, comprising a base member including an annular series of arcuate wedge members, arranged with their tapered ends 20 toward the center of the circle, and a cargo-supporting member mounted on the base member and provided with a rounded bottom.

25 5. A testing device for cargo adapted to simulate the movements of a ship, comprising a dished base member, a rockable member having a rounded bottom mounted on the base member, said rockable member having a radius of curvature smaller than that of the base member, means 30 for preventing movement of the rockable member in one plane, and means for rocking the member in a plane at right angles to the first-mentioned plane.
